SOLE-FITTING MACHINE

George Hazelton, Leicester, England, assignor to
 United Shoe Machinery Corporation, Borough
 of Flemington, N. J., a corporation of New
 Jersey

Application January 17, 1939, Serial No. 251,380
 In Great Britain February 2, 1938

13 Claims. (Cl. 12—31.5)

This invention relates to machines for beveling the rear ends of attached soles of shoes in the manner disclosed in United States Letters Patent No. 2,027,431, granted January 14, 1936, upon an application filed in the names of Hazelton, James and Bacon, for reception in V-shaped channels formed in the breasts of built-up leather heels to be attached to the shoes.

It is an object of the present invention to provide an improved machine of the same general type as that disclosed in United States Letters Patent No. 2,017,151, granted October 15, 1935, on an application filed in the names of Hazelton, James and Bacon. In order to form attractive joints between the upper breast corners of the heel and the sole of a shoe such as disclosed in United States Letters Patent No. 2,027,431, the lateral margins of the beveled rear end of the sole should extend to but not forwardly of the heel-breast line. Accordingly, the width of the lateral margins of the bevel at the rear end of the attached sole of the shoe should be approximately equal to the depth of the end portions of the V-shaped channel formed in the breast of the heel, irrespective of the thickness of the sole. The lateral portions of the V-shaped sole-receiving channels formed in the breasts of heels of different sizes are of uniform depth and accordingly it is desirable that the lateral margins of the bevel formed on the attached sole shall be of the same width regardless of the thickness of the sole.

With the above object and considerations in view, and in accordance with a feature of this invention, there is provided a sole-fitting machine comprising a support for the rear end of a sole, a knife having a cutting edge, means for initially moving the knife to cause said cutting edge to be forced against one face of the sole, and means for imparting a second movement to the knife in a path which is disposed at an angle to said one face and extends from said one face of the sole to the other thereby trimming material from the sole by a beveling cut.

The sole support of the illustrated machine has the form of a cutting bed which is interposed between the rear end of an attached sole of a shoe and the bottom of the shoe and which has a shear edge past which the cutting edge of the knife reciprocates. The knife, and a carrier having a guideway in which the knife is reciprocated to trim the sole, are mounted for pivotal movement together about an axis which is coincident with the shear edge of the cutting bed, the arrangement being such that the retracted

knife which is in a raised position above the cutting bed when the machine is idle, is swung bodily downward about said axis until its cutting edge is forced against the outer face of the sole preparatory to trimming the sole. The 5 knife is then moved forwardly in the guideway of the carrier, the cutting edge of the same traveling from the outer to the inner face of the rear end of the attached sole of the shoe and past the shear edge of the cutting bed to trim material 10 from the sole by a beveling cut. It will be appreciated that in making the beveling cut the cutting edge of the knife travels the same distance through the sole regardless of the thickness of the same, since the distance between the shear 15 edge of the cutting bed and the line of engagement of the cutting edge of the knife, when it is initially swung against the sole as above described, is always the same. Accordingly, the beveling cut is always of the same width regardless of the thickness of the sole, the width of the cut being approximately equal to the depth of the lateral portions of the V-shaped sole-receiving channel formed in the breast of the heel. It will be noted that although the width 20 of the beveling cut is constant, the angle of the bevel varies in accordance with the thickness of the sole. However, since the heel is compressed slightly during the heel-attaching operation, the sides of the V-shaped channel formed in the 25 breast of the heel are forced effectively against the beveled portion of the sole irrespective of the angle of the beveling cut.

The various features of the invention will be understood and appreciated from the following 35 detailed description read in connection with the accompanying drawings, in which

Fig. 1 is a side view, partly in section and partly broken away, of an illustrative machine;

Fig. 2 is a plan view, partly broken away, of the 40 machine;

Fig. 3 is an enlarged view, partly in section and partly broken away, of the operating head of the machine;

Fig. 4 shows in front elevation a cutting bed 45 for supporting the heel end of an attached sole of a shoe, a movable knife for trimming the sole by a beveling cut, and presser rolls movable with and ahead of the knife for forcing the sole against the cutting bed; 50

Fig. 5 is a section on the line V—V of Fig. 4 showing the trimming knife in its raised position over the cutting bed when the machine is idle;

Figs. 6 and 7 are sections on line VI—VI of 55

Fig. 4 during two different stages of the sole-trimming operation;

Fig. 8 is a perspective view of the heel end of a shoe which has been operated upon by the above machine;

Fig. 9 is a perspective view of a heel to be attached to the shoe of Fig. 8; and

Fig. 10 is a side view of the heel end of the shoe with the heel attached.

10 The illustrated machine is described with reference to trimming the attached sole 20 of a shoe 22 for the reception of a prefinished built-up leather heel 24 (Figs. 9 and 10). The sole is trimmed to a predetermined length by a beveling 15 cut 26 (Figs. 7, 8 and 10) the beveled rear end 28 of the sole of the finished shoe fitting in a transverse channel 30 (Fig. 9) formed in the breast of the heel 24 of the shoe, as illustrated in Fig. 10. The various advantages of such a 20 construction are set forth in the above-mentioned United States Letters Patent No. 2,027,431.

The illustrated machine, which is similar in many respects to the machine disclosed in the above-mentioned United States Letters Patent 25 No. 2,017,151, is provided with a jack 32 (Fig. 1) comprising a shoe supporting plate 34 which, as viewed in plan, has an outline similar to that of the heel end of the insole of the shoe, and a post 36 (Fig. 1) into which a depending extension of plate 34 is threaded. The post 36 is 30 slidable in a cylindrical bore 38 of a pedestal 40 and has a slot 42 through which passes a screw 44 threaded into the pedestal. When the machine is idle the post 36 is held in a raised position by a spring 46 which fits in a bore of the post and has its lower end resting upon the screw 44.

The pedestal 40 is mounted for sliding movement in a guideway 48 (Figs. 1 and 2) formed in 40 a forwardly projecting flange of the machine frame 50, the arrangement being such that the jack is moved forwardly to a loading position to place the shoe upon the jack and is then moved rearwardly until the rear end of the shoe engages 45 a back gage 52 (Figs. 1 and 3).

The back gage 52 may be moved into different operative positions along a guideway 54 (Fig. 3) in accordance with the length of a heel which is to be attached to the shoe, and is measured in a 50 heel gage (not shown). The heel gage, the back gage, and mechanism for operatively connecting said gages are similar to corresponding means disclosed in United States Letters Patent No. 1,847,244, granted March 1, 1932, on an application filed in the names of Hazleton and Ricks, and need not be further described herein. Secured to the back gage by screws 55 (Fig. 3) is a 55 forwardly projecting finger 56 which is arranged to overlie the bottom of the positioned shoe, and prevents the rear end of the shoe from being tipped upwardly by the operator.

As the shoe mounted upon the jack 32 is moved rearwardly along the guideway 48, the rear end 58 (Figs. 3 and 8) of the attached sole of the 60 shoe is guided over a wedge-shaped cutting bed or sole support 60 and under a straight cutting edge 62 (Figs. 4 to 7) of a knife 64 which, when the machine is in its raised position shown in Fig. 5. After the shoe has been moved into engagement with the back gage 52 the operator depresses a treadle 66 (Fig. 1) causing, through mechanism which will be described later, the forward end of a lever 68 to move the post 36 upward, thereby forcing the heel end of the shoe 65 bottom against the lower face 70 of the cutting

bed 60. The cutting bed 60 is secured to the main frame 50 by a pair of screws 72 (Fig. 3) which pass through elongated openings 74 in the main frame and are threaded into depending flanges 76, respectively, at opposite sides of the cutting 5 bed 60. It will be noted (Fig. 3) that the lower face 70 of the cutting bed 60 is in alignment with the shoe-engaging face of the finger 56 which is secured to the back gage 52.

The lever 68 (Fig. 1) through which the shoe 10 is raised, is pivoted at 78 to the main frame 50, and has its front end constantly urged downward by a spring 80. The rear end of the lever 68 is connected by a vertical link 82 to a horizontal link 84, the forward end of which is pivoted to 15 a rod 86. A rod 87 is connected at its lower end to the treadle 66 and at its upper end to a central portion of the link 84. As will appear presently, by lowering the rod 86 (Figs. 1 and 3) the cutting edge 62 of the knife 64 is swung into engagement with the heel end 58 of the sole supported by the cutting bed 60, as illustrated in Fig. 6, preparatory to moving the knife forwardly and downwardly in a rectilinear path to trim the sole by the beveling cut 26 (Figs. 7, 8 and 10). When the treadle 66 is first depressed by the operator the link 84 is moved in a counterclockwise direction about the vertical link 82 causing, through mechanism which will be described later, the knife to be swung bodily from its raised position shown in Fig. 5 into engagement with the sole mounted upon the cutting bed 60, as illustrated in Fig. 6. Upon continued depression of the treadle 66 (Fig. 1) the link 84 is moved in a clockwise direction about the rod 86 causing the 25 overlusted counter portion of the shoe upper to be forced against the lower face 70 of the cutting bed 60 thereby clamping the shoe against movement in the machine.

The end portions of channels 30 (Fig. 9) formed in the breasts of heels 24 of different sizes are usually of the same depth. It will be appreciated that in order to obtain an attractive joint between the upper breast corners of the heel and the sole of the finished shoe, the lateral margins of the beveled rear end 28 of the sole should extend to but not forwardly of the heel-breast line 88 (Fig. 8). Accordingly, it is desired that the width of the lateral margins of the beveled portion 28 of the sole shall be approximately equal to the depth of the end portions of the channel 30 irrespective of the thickness of the sole. It will be appreciated that the heel is compressed slightly during the heel-attaching operation with the result that in the finished shoe the sides of the V-shaped channel are effectively forced snugly against the beveled rear end 28 of the sole, irrespective of the angle of the beveling cut 26.

The cutting bed 60 has a serrated face 90 (Figs. 4 to 7) against which the sole is forced by presser rolls 92 which, as will appear later, move with and ahead of the knife 64 during its trimming movement. Extending from one side of the cutting bed 60 to the other is a cylindrical groove 94 (Figs. 4 to 7). The knife 64 is moved forwardly and downwardly to make the beveling cut 26 until its cutting edge 62 has moved to a position just forward of an edge 96 formed by the intersection of the groove 94 and a smooth portion of the face 90 of the cutting bed 60, as illustrated in Fig. 7. It will be noted that the forward portion 98 (Figs. 6 and 7) of the cutting bed 60 serves to support portions of the sole which are located a short distance ahead of the breast line 88 (Fig. 8) against being depressed by the action 75

of the knife 64. With such an arrangement it has been found that the knife 64 severs the sole with a clean cut at the edge 96 of the cutting block 60, which edge may be referred to as a shear edge.

The knife 64 is secured in a groove 100 (Fig. 3) of a slide 102 by a bolt 104 which passes through an open-ended slot 106 of the knife and fits in alined cylindrical bores in the slide 102, a plate 108 which is secured by screws 109 to the slide, and an upstanding bracket 110, the bolt 104 being clamped against the under side of the knife through the provision of a nut 112 threaded onto the upper end of the bolt. It will be understood that since the slide 102 is normally secured to the knife 64 it may be considered as constituting part thereof.

The attached soles of shoes are of varying thicknesses and, accordingly, it is desirable to swing the retracted knife 64 about an axis 114 (Figs. 2 and 4) which is coincident with the shear edge 96 so that the cutting edge 62 of the knife can be moved from the position illustrated in Fig. 5 into engagement with the sole (Fig. 6) preparatory to trimming the sole by the beveling cut 26 (Fig. 7). It will be appreciated that if the cutting edge 62 of the knife 64 were not swung into engagement with the sole, as above described, before reciprocating the knife to trim the sole, the beveled rear ends 28 of the soles would be of varying widths in accordance with the thickness of the sole and would therefore not be of a uniform width equal to the depth of the lateral margins of the channel 30 formed in the breast of the heel.

When the machine is idle the knife 64 occupies a position in which its cutting edge 62 is located well above the cutting block 60, as shown in Fig. 5, thereby providing a gap 116 which is wide enough to receive the rear end 58 of the attached sole of the shoe being positioned in the machine. In order initially to swing the cutting edge 62 of the knife 64 against the sole as above described, the slide 102, which is mounted for movement in a rectilinear guideway 118 (Fig. 3) of a carrier 120, is mounted for swinging movement, together with the carrier, upon bearing pins 122 supported by the main frame 50, the axes of the pins 122 being coincident with the axis 114, which, as above stated, extends along the shear edge 96 of the cutting bed 60.

The slide 102 has at its rear central portion a pair of spaced bosses 124 (Figs. 2 and 3) in which is secured a rod 126 (Fig. 3). Mounted upon the rod 126 is a sleeve or cam roll 128 fitting in an arcuate slot 130 formed in an upstanding flange 132 (Figs. 2 and 3) of an operating slide 134 which is movable along a rectilinear guideway 136 (Fig. 3) of a bracket 138 (Fig. 2 and 3). The bracket 138 is mounted upon shafts 140 supported by the main frame 50 and may be initially swung about the shafts to insure that the arcuate guideway 130 (Fig. 3) is centered about the axis 114 (Figs. 2 and 4) through the following arrangement. Located at opposite sides of the bracket 138 (Figs. 2 and 3) are two bores into which are threaded sleeves 142. Passing through openings in the respective sleeves 142 (Fig. 3) are screws 144 which are threaded into the main frame 50. The screws 144 are normally tightened so that the bracket 138 is held fixed, clockwise movement of the bracket about the shafts 140 being prevented by the engagement of the sleeves 142 with the main frame 50, and movement of the bracket 138 in a counterclockwise direction being prevented by washers 146 which are inter-

posed between the bracket and the heads of the screws 144.

The operating slide 134 has a pair of downwardly projecting bosses 148 bored to receive a pin 150 connecting the slide 134 to a link 152. The rear end of the link 152 is pivoted to a pin 154 which is secured to a block 151 fitting in an arcuate slot 153 of a driving link 155. The block 151 is carried by a yoke 156 and may be secured in different adjusted positions along the slot 153 through the provision of a screw 158 which is threaded into the yoke and has its end forced against the link 155. The upper end of the link 155 is pivoted to the rear end of a bifurcated lever 162 (Figs. 2 and 3) pivoted at its forward end to the main frame 50. The lower end of the link 155 is pivoted to a slide 164 which is movable in a guideway 166 and has secured to it a cam roll 168 fitting in a cam groove 170 of a cam 172 mounted upon a drive shaft 174. Upon tripping a clutch 176 (Fig. 1) the shaft 174 is rotated through a complete revolution and then comes to rest.

When the machine is idle the cam roll 128 (Fig. 3) which is secured for movement with the knife 64, as above described, is forced against the upper end of the slot 130 through the provision of a pair of connecting links 178 (Figs. 1 and 3) pivoted upon pins 179 secured to opposite sides of the carrier 120. Mounted upon a rod 180 (Fig. 3) secured to the lower ends of the links 178 is a sleeve 181 having depending flanges 182 which straddle and are pivoted to the upper end of the rod 86. The rod 86 is normally urged upwardly through the link 84 and the treadle rod 87 by a spring 184 (Fig. 1) the lower end of which is secured to the treadle 66 and the upper end of which is secured to the main frame. When the sleeve 128 (Fig. 3) carried by the slide 102 is in engagement with the upper end of the slot 130 the knife 64 is in its raised position shown in Fig. 5 above the cutting bed 60.

In order to insure accurate control of the beveling cut 26 (Figs. 7, 8 and 10) the machine is provided with the above-mentioned rolls 92 which advance with the knife 64 and press on the outer face of the attached sole of the shoe, one at each side thereof just in front of the cutting edge 62 of the knife. The rolls 92 are yieldable upward in paths disposed at approximately right angles to the line of the cut and insure against the knife 64 picking up the sole as it trims the same.

The upstanding bracket 110 (Figs. 2 and 3) has a rearwardly extending lug 186 to which is secured a laterally extending pin 188 normally fitting in open-ended slots 190 (Fig. 3) of two upstanding flanges 192 (Figs. 2 and 3) formed integral with the plate 108, which, as above stated, is secured by the screws 109 to the slide 102. With the above arrangement the bracket 110 may be quickly and accurately positioned upon the plate 108. The bracket 110 has pivoted to it right and left pairs of parallel links 194 (Figs. 2 and 3) 196 (Fig. 3) the forward end portions of which pairs are pivoted in bifurcated portions of corresponding blocks 198 (Figs. 2 and 3), one carried by the links 194, 196 at one side of the bracket 110 and the other carried by the links 194, 196 at the other side of the bracket. Secured to the bracket 110 is a flange 200 (Figs. 2 and 3) into which a pair of screws 202 are threaded. Each of the screws 202 is forced against a retaining collar 204 (Fig. 3) engaging the upper end of a corresponding compressor spring 206, the lower end of which engages an inwardly extending flange 208.

- of an adjacent link 196. The arrangement is such that the springs 206 constantly urge the blocks 198 downward in paths disposed at right angles to the direction of movement of the knife-carrying slide 102, the degree of compression of the springs 206 being regulated by adjusting the screws 202 in the flanges 200. Downward movement of the blocks 198 is limited by the engagement of rearward extensions 210 of the respective links 194 with stop screws 212 threaded into a rearwardly extending portion of the flange 200. The idle positions of the blocks 198 may be raised or lowered by altering the setting of the screws 212 in the flange 200.
- 18 In the forward face of each of the blocks 198 is a horizontal T-shaped channel 216 (Fig. 3) and in each channel is a T-shaped slide 218 into which is threaded a locking screw 220 (Figs. 2 and 3) for normally retaining the slide in a fixed position in the channel. When the screws 220 are released the T-shaped slides 218 may be adjusted in their corresponding T-shaped channels 216. The locking screws 220 fit in bores of corresponding roll carriers 222 and are provided with lock 25 nuts 224 which normally clamp the roll carriers fast to their corresponding T-shaped slides 218, but which may be released preparatory to varying the angular positions of the roll carriers 222 upon the slides. The lower end portions of the roll carriers 222 are bifurcated, as shown in Fig. 4, and carry pins 226, respectively, (Figs. 2 and 4) on which the corresponding rolls 92 are rotatably mounted. The presser rolls 92 are located just above the cutting edge of the knife 64 (Figs. 4 to 30 7) and their axes lie in a plane which is approximately perpendicular to the direction of movement of the knife-carrying slide 102. The rolls 92 are cylindrical and are conveniently about one-half an inch in length and diameter.
- 35 40 It will be appreciated that the positions of the presser rolls 92 can be adjusted lengthwise of the cutting edge 62 of the knife 64 and that the angular positions of the rolls can be adjusted in a plane arranged at right angles to the direction of the cutting stroke of the knife. Moreover, the rolls 92 can yield upwardly away from the cutting edge of the knife during the cutting stroke of the same, the degree of compression of the springs being initially regulated through the provision of 45 the set screws 202. As the cutting edge 62 of the knife 64 advances into the sole the presser rolls 92 traveling with the knife engage the upper surface of the sole at each side thereof and press the sole firmly against the serrated upper face 90 50 of the cutting bed 60, the beveled rear end 28 of the sole passing between the knife and the rolls, as illustrated in Fig. 7. The chip 228 severed from the sole is left between the lower surface of the knife 64 and the serrated face 90 of the cutting bed 60.
- 55 60 In order to trim the rear end 58 (Fig. 8) of the attached sole 20 of the shoe 22 by the beveling cut 26 (Figs. 7, 8 and 10) for the reception of the heel 24, the operator places the shoe upon the jack 65 and slides the jack with the shoe mounted on it rearward, the rear end 58 of the sole being fed over the cutting bed 60 until the rear end of the shoe engages the back gage 52. The operator then depresses the treadle 66 causing the knife 64, together with the carrier 102 in which the knife reciprocates, to be swung bodily downward about the axis 114 until the cutting edge 96 of the knife has been forced against the sole, as shown in Fig. 70 75, further depression of the treadle 66 causing the jack 32 to be raised and thereby to force the over-

lasted counter portion of the shoe upper against the lower face 70 of the cutting bed 60. The one-revolution clutch 176 (Fig. 1) is then tripped, causing the knife 64 to be moved forwardly and downwardly past the shear edge 96 of the cutting bed 60 to the position illustrated in Fig. 7, to trim the sole by the beveling cut 26. The operator then releases the treadle 66 and, after moving the jack to its forward loading position, removes the shoe from the jack.

Having described the invention, what I claim as new and desire to secure by Letters Patent of the United States is:

1. A sole-fitting machine having, in combination, a support for the rear end of a sole, a knife having a cutting edge, means for initially moving the knife to cause said cutting edge to be forced against one face of the sole, and means for imparting a second movement to the knife in a path which is disposed at an angle to said one face and extends from said one face of the sole to the other thereby trimming material from the rear end of the sole by a beveling cut.

2. A sole-fitting machine having, in combination, a support for the rear end of a sole, a knife having a cutting edge, means for initially moving the knife to cause its cutting edge to be forced against one face of the sole, and means for imparting a cutting movement to the knife in one of a plurality of possible paths converging to a single fixed axis, the particular one of said paths in which the knife is moved being determined by the thickness of the sole.

3. A sole-fitting machine having, in combination, a support for a sole, a knife having a cutting edge, a carrier having a guideway in which the knife is movable, means for swinging the carrier and the knife about a fixed axis to cause the cutting edge of the knife to be forced against one face of the sole, and means for moving the knife along the guideway of the carrier and toward said axis to trim material from the rear end of the sole by a beveling cut.

4. A sole-fitting machine having, in combination, a fixed cutting bed having a face constructed and arranged to be engaged by a sole, a knife, means for moving the knife from a retracted position toward an axis which lies approximately at said face of the cutting bed to trim material from the sole by a beveling cut, and means for swinging the retracted knife with relation to the cutting bed about said axis during each cycle of operation of the machine.

5. A sole-fitting machine having, in combination, a support for a sole, a knife, a carrier having a guideway, means constructed and arranged to move the knife together with the carrier away from the support to enable the operator to position the rear end of the sole upon the support, said means also being constructed and arranged to move the knife together with the carrier toward the support for moving the cutting edge of the knife against the sole preparatory to trimming the sole, and means for moving the cutting edge of the knife which is in engagement with the sole from the outer to the inner face of the sole to trim the rear end of the sole by a beveling cut.

6. A sole-fitting machine having, in combination, a cutting bed constructed and arranged to be interposed between the heel end of an attached sole of a shoe and the bottom of the shoe, a knife, a carrier having a guideway, means for moving the knife in said guideway to trim material from the rear end of the sole by a beveling cut, and means constructed and arranged to

move the carrier to a predetermined position away from the cutting bed after the sole has been trimmed and to hold the carrier in said position to facilitate positioning a shoe to be operated upon in the machine.

7. A sole-fitting machine having, in combination, a fixed cutting bed constructed and arranged to be interposed between the heel end of an attached sole of a shoe and the bottom of the shoe, said cutting bed having a shear edge, means for positioning the heel end of the shoe with the sole upon the cutting bed, a knife, means for moving the knife in a rectilinear path extending past said shear edge to trim the rear end of the sole by a beveling cut, and means for varying the angle of the path of rectilinear movement of the knife with relation to the cutting bed in accordance with the thickness of the sole supported upon said cutting bed in order to insure that the heel ends of soles of different thicknesses shall be beveled to a uniform width.

8. A sole-fitting machine having, in combination, a support for a sole, a knife having a straight cutting edge, a carrier having a rectilinear guideway in which the knife is movable, means for swinging the carrier and the knife together about an axis which extends along the sole-engaging portion of the support and is approximately parallel to the cutting edge of the knife to force the cutting edge of the knife against one face of the sole, and means for moving the knife in said guideway with its cutting edge traveling from one face of the sole to the other and past said axis to trim material from the rear end of the sole by a beveling cut.

9. A sole-fitting machine having, in combination, a cutting bed constructed and arranged to be positioned between the heel end of an attached sole of a shoe and the bottom of the shoe, means for positioning the shoe in the machine, said cutting bed having a sole-engaging face in which is formed a groove extending widthwise of the sole of the positioned shoe, a knife having a cutting edge, a carrier having a guideway in which the knife is reciprocated, means for swinging the carrier and the knife together about an axis extending along a shear edge defined by the groove and the sole-engaging face of the cutting bed in order to force the cutting edge of the knife against the outer face of the heel end of the sole, and means for moving the knife forwardly and toward the shoe upper in the guideway of the carrier to cause the cutting edge of the knife to travel from the outer to the inner face of the sole and past said shear edge of the cutting bed to trim material from the rear end of the sole by a beveling cut.

10. A sole-fitting machine having, in combination, a support for a sole, a knife having a cutting edge, a carrier having a guideway in which the knife is reciprocated, said carrier being mounted for pivotal movement about an axis, an operating slide having an arcuate slot which is centered about said axis, a cam roll carried by the knife and constructed and arranged to fit

in the arcuate slot of the operating slide, means for moving the knife together with the carrier toward the support about said axis to move the cutting edge of the knife into engagement with the sole, and means for actuating the operating slide to cause the knife to move toward said axis thereby trimming material from the rear end of the sole by a beveling cut.

11. A sole-fitting machine having, in combination, a cutting bed constructed and arranged to be interposed between the rear end of an attached sole of a shoe and the bottom of the shoe, said cutting bed having a sole-supporting face in which is formed a groove, means for moving the knife toward the cutting bed and into the groove to trim material from the rear end of the sole by a beveling cut, and yieldable presser members for progressively forcing the heel end of the sole against said face of the cutting bed immediately in advance of the knife to insure that the sole shall not be picked up by the knife while trimming the sole.

12. A sole-fitting machine having, in combination, a wedge-shaped cutting bed constructed and arranged to be positioned between the rear end of an attached sole of a shoe and the bottom of the shoe, said cutting bed having a sole-supporting face provided with a groove which forms a shear edge with said face, a knife having a cutting edge, means for moving the knife toward and past said shear edge to trim material from the rear end of the sole by a beveling cut, and yieldable presser members movable with the knife and constructed and arranged progressively to force the sole immediately in advance of the cutting edge of the knife against the cutting bed to insure against the sole being picked up from the cutting bed by said knife during the trimming operation.

13. A sole-fitting machine having, in combination, a jack for supporting a shoe, a fixed cutting bed constructed and arranged to be interposed between the heel end of an attached sole of a shoe and the overlasted counter portion of the shoe, a knife having a cutting edge, a carrier having a guideway in which the knife is movable, said carrier being mounted for pivotal movement about a fixed axis, an operating slide having an arcuate slot which is centered about said axis, a cam roll carried by the knife and constructed and arranged to fit in the arcuate slot of said operating slide, means comprising a manually operated member constructed and arranged to move the knife and the carrier toward the cutting bed from their inoperative positions away from the cutting bed until the cutting edge of the knife has been forced against the sole and then to raise the jack thereby forcing the overlasted counter portion of the shoe against the cutting bed, and means for actuating the operating slide to move the knife toward and past said axis to trim material from the rear end of the sole by a beveling cut.

GEORGE HAZELTON. 65
